CORE BIT

Charles J. Koebel, Detroit, Mich.

Application January 23, 1937, Serial No. 121,935
Renewed November 3, 1938

2 Claims. (Cl. 255—72)

The invention relates generally to diamond bits or tools and it has particular relation to a diamond core bit for use by geologists and others for obtaining samples of different earth strata.

5 In general a core bit includes a tubular member having cutting elements on its end, and rotation of the bit about its longitudinal axis results in the cutting of an annular opening and thereby separates a central core from the strata 10 through which the bit is operated. In order that geologists and others may accurately determine the depth of various strata it is important that the core remain unbroken as much as possible so that the position of different elements in the 15 core may accurately be determined longitudinally thereof. It is therefore important that the bit should cut efficiently so as to obtain a smooth and non-broken core and also that it last or be durable.

20 One object of the present invention is to provide an improved core bit which will last for a longer period of time and which will enable obtaining a smooth and non-broken core.

Another object of the invention is to provide an improved core bit wherein the diamonds may be distributed uniformly and with the diamonds projecting equal amounts so as to thereby enable obtaining a uniform distribution of the cutting forces and to prevent uncut portions of the 0 strata from engaging the metal that holds the diamonds.

Another object of the invention is to provide an improved core bit that may be altered, repaired or renewed readily by diamond setters in the field.

5 Other objects of the invention will become apparent from the following specification, the drawing to which it relates, and from the claims hereinafter set forth.

For a better understanding of the invention reference may be had to the drawing wherein

Fig. 1 is an end view of a core bit constructed according to one form of the invention.

Fig. 2 is a cross sectional view taken substantially along the line 2—2 of Fig. 1.

Fig. 3 is a detailed view illustrating one of the lugs forming a part of the bit shown by Fig. 1.

Fig. 4 is a view generally similar to Fig. 1 but illustrating another form of the invention.

Figs. 5, 6 and 7 are views similar to Fig. 2 but illustrating still other forms of the invention.

Referring to Figs. 1 and 2, the body of the core bit is indicated at 10, and it will be understood that this is to be fastened to the end of a rotary

drill shaft of tubular character so as to permit the rock or other core to pass upwardly through the shaft. The cutting face of the body 10 is provided with a series of radially disposed and circumferentially spaced slots 11, and it will be noted that these slots have a substantial depth linearly of the body. In each of the slots a slug 12 of comminuted metal alloy is disposed and the slug is securely fastened in place in any suitable manner, such as by brazing or by peening of the body metal over portions of the slug metal. The slugs might also be cast in place in which event they would become tightly bound in the slots. Brazing is indicated at 13 in Fig. 2 and this brazing may be effected also along the sides 15 of the slug. Each of the slugs is provided with small diamonds 15 having points projecting from the surface of the slug and it will be noted that the radially inner and outer sides, as well as the end surface of the slugs, are provided with 20 these diamonds. As will be evident from both Figs. 1 and 2, the diamonds are distributed and staggered so that one diamond won't follow in the cutting path of an adjacent diamond. The end desired in this connection is that the cutting loads will be equally distributed over all of 25 the diamonds to avoid premature wearing of any one or more diamonds and also to insure complete removal of the rock as the bit progresses to avoid uncut portions of the rock engaging the 30 slug or body metal between the diamonds. If such engagement of uncut portions of the rock with the body or slug metal were permitted the body and slug metal would wear away and the anchorage of the diamonds might thus become 35 impaired.

Slugs of comminuted alloy with diamonds imbedded therein may be made according to the processes disclosed in the patent to Koebel No. 1,848,182, or in the application for patent referred to therein, Serial No. 586,238, filed January 12, 1932. In the present case, however, it may be mentioned that the diamonds would only be distributed along the cutting peripheral portions of the slug although if found desirable the 45 diamonds might be distributed throughout the comminuted alloy slugs and then as the diamonds wore down, the slug and body metal would necessarily wear away so as to expose new diamond points.

Fig. 4 is similar to Fig. 1 and in this structure slots 16 are provided that are angled to radii. In this construction a somewhat greater circumferential space will exist between the radially outer portions of the slugs for accommodating 50 55

additional diamonds or smaller slugs to be referred to hereinafter, and which ordinarily would be inserted by diamond setters in the field. Moreover the strength of the slugs is slightly greater because of their angled positions, and it is a little easier to distribute and to stagger them.

In the construction shown by Fig. 5 peripheral-
ly extending slugs 18 of substantially greater
length are provided and each of these may have
a rib portion 19 adapted to fit in a groove 20
in the end face of the body. The slugs may be
held in position by peening over the metal as
indicated at 21 or by other suitable means such
as brazing as hereinbefore mentioned. The ad-
jacent ends of the slugs may be connected by
brazing such as indicated at 22, and if desired a
portion of the body 10 may extend between the
ends of the slugs and the ends of the slugs be-
brazed to the body portion.

The structure shown by Fig. 6 is substantially
the same as that shown by Fig. 2 excepting that
small comminuted alloy slugs 24 are provided in
the side wall of the body 10. The slugs shown
are ground and have small diamonds 25 project-
ing beyond the side surface of the body. Such
slugs would be distributed circumferentially and
would be staggered so that one diamond would
not exactly follow the cutting line of an adjacent
diamond. It will be understood that the slugs
are held in place by brazing, peening, or other
suitable means and if desired the opening for the
slug may be tapered and the slug tapered corre-
spondingly.

In the structure shown by Fig. 7 instead of
using the type of slug shown by Figs. 1, 4, and 5,
slugs such as indicated at 24 in Fig. 6 are used.
These slugs are distributed over the side sur-
faces of the body 10, as well as the end face. It
will be appreciated that the use of small slugs
having diamonds imbedded therein in a struc-
ture such as this or such as shown in Fig. 6 read-
ily enables the diamond setters in the field to
properly insert diamonds without any difficulty.
It would only be necessary to drill the same type
of holes at all points and insert the slugs, and

then secure the latter in place by peening or braz-
ing. No conventional setting of diamonds would
be necessary.

It will be understood that small slugs such as
shown at 24 in Figs. 6 and 7 could be employed at
various points in any of the other structures
shown. For example, such slugs could be used
in the side wall of the body such as illustrated in
Fig. 6 or sockets could be drilled between the slugs
12 and 16 in Figs. 1 and 4 for receiving the slugs 24.
Also, such sockets for additional slugs 24
could be formed partly in the slugs 12 or 15 and
partly in the metal between the latter slugs. In
other words, slugs 24 could be inserted at any
desired point over the working surfaces of the bit.

Although more than one form of the invention
has been described and illustrated in detail, it
will be apparent to those skilled in the art
that various modifications may be made without
departing from the scope of the appended claims.

What is claimed is:

1. A core bit comprising a tubular body, the
tubular wall of said body being rounded in
radial cross section at one end and provided with
transverse slots therethrough, segmental slugs 25
seated in said slots and conforming in contour to
the inner and outer walls of said tubular body as
well as to the radially rounded cross section of
said tubular wall, said slugs forming with the
intervening end portions of said tubular body a 30
nose for the core bit, said slugs comprising sin-
tered comminuted metal alloy each having em-
bedded therein a plurality of cutting stones.
2. In a core bit, a tubular body having one end
rounded in radial cross-section and provided with 35
transverse slots of substantially equal width
throughout their length; and reversible slugs, of
substantially equal width throughout their length
and having a rounded surface at one end con-
forming substantially to the rounded end of the 40
tubular body, seated in said slots; and a plurality
of diamonds arranged in a curved series on the
rounded surface of each slug.
